METHOD AND APPARATUS FOR FORMING
BANDAGE STRIPS

William D. Young, Greenville, S. C.

Application November 30, 1942, Serial No. 467,351

15 Claims. (Cl. 112—2)

This invention relates to the manufacture of bandage strips or pads, sanitary napkins, and the like, and more especially to an improved forming apparatus for accurately feeding a continuous sheet of cover over a continuous lap of filler material.

In the manufacture of bandages, such as disclosed in my co-pending patent application entitled Bandage and method of making same, Serial No. 460,252, filed September 30, 1942, it is desirable to form the body portion thereof in one continuous length, and then cut this length into shorter lengths so that bandages can be made therefrom. One of the chief defects in many bandages resides in the positions of the seams which serve to form a tubular cover around the filler material. Unless these seams occupy the proper positions away from the contact surface of the bandage, the ribbed surfaces created by the seams will serve to irritate the wound surfaces of the patient's body. Furthermore, the seams are usually formed near two joined edges of the tubular cover and then the cover is turned inside-out and over the filler material. After turning the cover, the projecting edges of the cover, which formerly were on the exterior, will be disposed inside and adjacent the seam, to thereby add to the size of the rib at the seam line.

It is an object of this invention to provide a hollow bandage former having means for sewing the side edges of a longitudinally moving cover strip together while passing over the exterior of the former to make a tubular cover, and also having means for turning and then directing the seamed cover reversely inside of the former and over a continuously moving bat of filler material to thereby encase the filler material.

It is another object of this invention to provide a former of the class described in combination with means for rotating the tubular cover and associated seam about the longitudinal axis of the hollow former after the cover passes the sewing mechanism. This rotation of the cover on the exterior of the former causes the seam line to be positioned away from the contact face of the bandage where no injury or discomfort will be inflicted upon the patient when the bandage is used.

It is another object of this invention to provide a former having means for directing the longitudinal projecting edges of the tubular cover, which edges are normally disposed on the outside of the seam line, into substantially parallel relation to one of the faces of the cover. It is evident that much less space will be occupied by the projecting edges when disposed in parallel relation to one of the cover faces, and consequently, a smaller rib will be formed on the bandage when the cover is turned inside out and reversely directed over a bat of filler material.

It is another object of this invention to provide a former having an improved means for folding a traveling sheet of material substantially along its longitudinal center line and for guiding the edges of the folded sheet into substantially parallel superposed positions while being united by a sewing mechanism to form a tubular cover. Heretofore much difficulty has been encountered on account of the edges of the sheet of material deviating from the desired path of travel, resulting in one edge extending further beyond the seam line than the other. The present folding means positively defines the path of travel of each edge of the folded cover sheet, and therefore produces uniformity in the sewed tubular cover throughout its length.

Some of the objects of the invention having been stated, other objects will appear as the description proceeds when taken in connection with the accompanying drawings in which:

Figure 1 is a plan view of one form of apparatus for making a bandage strip or pad;

Figure 2 is a vertical sectional view taken along the line 2—2 in Figure 1, illustrating the supporting and primary forming mechanism for the bandage cover sheet;

Figure 3 is a sectional view taken along the line 3—3 in Figure 1 illustrating the approximate folded position of the cover sheet prior to the same entering the secondary bandage former;

Figure 4 is a sectional view taken along the line 4—4 in Figure 1;

Figure 5 is a sectional view taken along the line 5—5 in Figure 1;

Figure 6 is a sectional view taken along the line 6—6 in Figure 1, said view illustrating the cover sheet disposed within the secondary forming mechanism and in a more completely folded position than illustrated in Figure 3;

Figure 7 is a sectional view taken along the line 7—7 in Figure 1, illustrating the third formation of the bandage or pad cover sheet;

Figure 8 is an enlarged sectional detail view taken along the line 8—8 in Figure 1, said view illustrating the bandage cover after the folded edges have been united by a seam, and also illustrating a guiding means for turning the projecting cover edges, beyond the seam, to parallel positions to one of the faces of the tubular cover;

Figure 9 is an enlarged sectional detail view taken along the line 9—9 in Figure 1, further illustrating the projecting edges of the tubular cover when in a completely folded position against one of the faces of the tubular cover;

Figure 10 is a sectional view taken along the line 10—10 in Figure 1;

Figure 11 is a sectional view taken along the line 11—11 in Figure 1;

Figure 12 is an isometric view of one end of

the forming tube, illustrating the guiding mechanism for turning the projecting edges which are beyond the cover seam into substantially parallel relationship to one of the faces of the tubular cover;

Figure 13 is a schematic isometric view, illustrating the various folds of the cover material prior to the same encasing a lap of filler material, but omitting the forming apparatus;

Figure 14 is a plan view, similar to the upper right-hand portion of Figure 1, illustrating a slightly modified form of the invention in which the tubular cover and longitudinal seam are rotated around the exterior of the forming tube prior to said cover being turned inside-out and reversely directed to the interior of the tube and over the filler material;

Figure 15 is a sectional view taken along the line 15-15 in Figure 14;

Figure 16 is a sectional view taken along the line 16-16 in Figure 14;

Figure 17 is an isometric view illustrating another modified form of the invention in which at least two sheets of material are used for forming the cover sheet and in which two seams are employed at opposed edges of the sheets to form a tubular cover;

Figure 18 is an isometric view of the forming tube over which the tubular cover is formed, and through which the filler material and reversed cover are passed when forming the bandage;

Figure 19 is a transverse sectional view taken along the line 19-19 in Figure 17 illustrating the brush which compresses the edges of the upper cover layer into close contact with the outer edges of the lower layer prior to the seaming operation being effected;

Figure 20 is a transverse sectional view taken along the line 20-20 in Figure 17, illustrating the mechanism for turning the projecting edges of the tubular cover, which are disposed beyond the seam, into parallel relation to one of the faces of the bandage material;

Figure 21 is a transverse sectional view taken along the line 21-21 in Figure 17, said view being similar to Figure 20, except the projecting edges beyond the seam are turned to completely parallel positions to one face of the bandage cover;

Figure 22 is a longitudinal sectional view taken along the lines 22-22 in Figures 17 and 19.

Primary cover forming mechanism

Referring more particularly to the drawings, the numeral 10 denotes a framework for supporting the cover sheet roll and the primary forming mechanism therefor. In the form of the invention shown in Figures 1 to 13 inclusive, a single sheet of cover material such as gauze or the like is folded upon itself in a substantially U-shaped position while the same is traveling. This U-shaped sheet of material is then fed through a forming apparatus at an angle to the longitudinal travel of a continuous lap of filler material, and when the U-shaped cover reaches the former, it is turned inside-out over the former and lap of material and then directed in an opposite direction to the direction of travel of the lap, but on the outside of the former tube. While travelling in this opposite direction, the two edges of the folded sheet of material are united by a seam to form a tubular member, after which the tubular member is turned inside-out at the end of the former and reversely directed

over the lap of filler material. The framework 10 supports the cover sheet roll and the primary forming mechanism in such relative positions that the cover sheet will properly enter the secondary forming mechanism.

By observing Figure 2, it can be seen that the framework 10 has rotatably mounted therein as at 11 a vertically disposed shaft 12, said shaft projecting upwardly above the top of the framework a substantial distance and being adapted to support therearound a roll 14 of cover material 15. This roll 14 is adapted to rest upon a suitable base plate 17 which is fixedly secured upon the intermediate portion of shaft 12. A suitable washer or hub 18 is disposed around this same shaft, above the roll 14, to thereby create the necessary friction between the roll 14 and plate 17 and cause shaft 12 to turn as the material 15 is unwound.

It is necessary to provide means for retarding the rotation of roll 14 and shaft 12 as the material is unwound. Therefore, a grooved pulley 20 is fixedly secured upon the shaft 12, said pulley having the intermediate portion of a cord or flexible member 21 engaging a substantial portion of its periphery. This cord has one end thereof secured to the framework 10 as at 22, and has its other end weighted as at 23, thereby causing the cord to frictionally engage the pulley groove and thus retard its rotation. It will be noted that the portion of cord 21, which is directly above the weight 23, is adapted to pass downwardly and through an opening 24 in a bracket 25. The purpose of this bracket is to maintain the intermediate portion of cord 21 at the proper elevation relative to pulley 20, while the weight 23 creates the necessary friction.

After leaving the roll 14, the sheet of material 15 passes around a cylindrical knurled guide roll 26. The guide roll 26 is fixedly mounted upon a shaft 27, which, in turn, is rotatably mounted as at 28 in the framework 10.

The primary forming stages of the cover sheet 15 are effected immediately after the material leaves the cylindrical roll 26. This forming mechanism comprises a board 30 which has an arcuate periphery over which the cover slides. The vertex of the arcuate periphery of board 30 is disposed substantially along the longitudinal center line of the cover sheet 15, therefore the edges of the sheet of material will be curved inwardly toward each other at the upper and lower portions of the periphery so as to be concavo-convex in cross section. Board 30 is supported by a rod 31, which, in turn, is adjustably secured in a bracket 32. This rod may be moved longitudinally of the bracket 32 and adjusted to different positions by manipulating a set screw 33. Bracket 32 is adjustably secured on a vertically disposed rod 34 by means of a set screw 35, said rod 34 having its lower end supported by the framework 10.

When it is desired to swing the board 30 around the rod 34 as an axis, it is only necessary to manipulate the set screw 35. It is, of course, evident that by rotating the board 30 about rod 34, the amount of fold produced in the cover sheet 15 can likewise be varied. For example, the smaller the angle produced between the forming board 30 and that portion of the material which is disposed to the right of the former 30 (Figure 1), the less will be the amount of fold produced in the cover material. On the other hand, should the former 30 be disposed at right angles to the path of travel to the sheet of the

material 15, then the amount of forming would be at a maximum.

Secondary cover forming mechanism

After the primary forming stages have been effected and the sheet of cover material 15 has been folded along its longitudinal center line to substantially the position shown in Figure 3, it is fed into a forming apparatus broadly designated by the reference character 37. By observing Figures 5 and 6, it can be seen that the forming apparatus 37 has a U-shaped groove 38 therein, the length of which is substantially the same as the width of the cover sheet 15. Also it will be noted that this groove serves to further bend or fold the cover sheet to a position where the upper and lower folds will be substantially parallel, and where the edge of the upper fold will be disposed directly above the edge of the lower fold.

Tertiary bandage cover forming mechanism

The U-shaped cross-sectional formation of the cover sheet 15 is maintained until the sheet reaches angularly disposed guide edges 39, said edges 39 being disposed above and below the horizontal center line of the former 37 in Figures 4 and 5. In the present disclosure, the edges 39 are cut substantially at a 45° angle to the line of travel of the sheet of material 15 as it approaches the former 37. The purpose of these edges is to turn the U-shaped cover inside-out into a second U-shaped cover and to change the direction of travel of the cover at a right angle. In other words, by providing angularly disposed edges 39 at the point of change in direction of travel of the fabric cover, it is possible to locate the source of cover supply, such as roll 14, along one side of the bandage forming apparatus 37, and at the same time, maintain a positive control of the folded edges of the material while it travels beneath the sewing mechanism which, in turn forms a tubular fabric from the material.

By observing Figures 1 and 4, it can be seen that the angularly disposed edges 39 form one end of a second U-shaped member 40, and this U-shaped member has a hollow member 41 disposed therein. (See Figure 7.) The outer side walls of member 41 are disposed in spaced relation to the inner walls of U-shaped member 40 thereby forming a U-shaped groove 43. It is in this U-shaped groove 43 that the turned tubular fabric 15 is adapted to travel, said groove 43 being disposed substantially at right angles to the groove 38 previously described.

Although the grooves 38 and 43 are shown at right angles, it is evident that any desired angle could be present between these grooves without substantially changing the results, provided the edges 39 are cut at the proper angle to cause the folded material to feed from one groove to the other.

By referring to Figures 4, 10, and 11, it can be seen that the hollow member 41 is supported by the member 40 as at 45 and 46. Also in Figure 10, it can be seen that the open ends of U-shaped member 40 converge toward each other as at 40a thereby providing means for guiding the superposed edges of the cover material 15 toward each other prior to uniting the same. These superposed edges of the cover material travel to the right in Figure 10 from the points 40a and are united by a seam 48 or by other suitable means, said seam being provided by means of a sewing mechanism broadly designated by the reference character 50.

Seam guiding mechanism

Seam 48 forms the cover sheet into a tubular fabric, which at the time of formation, encases the exterior of the hollow forming tube 41. Since it is usually necessary to provide the seam 48 a substantial distance from the edges of the upper and lower cover folds, it is evident that projecting edges 15a will be provided beyond the seam. As heretofore stated, these projecting edges will serve to create a rib adjacent the seam line if the same are not properly folded into parallel position to one face of the cover sheet. In the present form of the invention, means are shown whereby both of these edges will be folded into parallel positions to each other and also parallel to one of the faces of the tubular member prior to the tubular member being turned and reversely directed over a lap of filler material to form a bandage strip.

In the disclosed form the invention the bandage is substantially rectangular in cross section and is adapted to have one face especially provided for contacting an injured portion of the body. Therefore, it is only necessary to turn the projecting edges 15a in a direction so that the same will be remotely disposed from the contact face of the bandage and away from the injury.

In order to effect this turning of the edges 15a, a suitable guide wire, or similar mechanism 52, is provided on the exterior of the hollow forming member 41 and near the end thereof. (Figures 1 and 12.) The seam 48 first engages the guide member 52 substantially along the horizontal center line of the hollow member 41 after which the seam is gradually directed upwardly in the manner shown in Figures 8 and 9. As the seam rises upwardly and travels longitudinally of the former 41, the projecting edges 15a are gradually turned over to the top side of the tubular fabric so that the edges will be parallel to the top face prior to turning the tubular member inside out and reversely directing the same to the interior of the hollow member and over a rectangular filler material 53, said filler material usually being cotton which is carded in such a manner that the fibers are disposed substantially parallel to the longitudinal center line of the bandage strip.

Figures 1, 10, 11, and 13 show the method of turning this tubular member inside out and reversely directing it to the interior of the former 41. When the edges 15a reach the end of tubular former member 41, these parallel edges are disposed on the top side of the tubular member as well as on the top side of the former 41. At the point of reversal, the tubular member and the projecting parallel edges 15a are fed into the interior of the former 41 to encase the filler material 53. Therefore, the projecting edges 15a will be turned to the inside of the tubular member and in a position where the same will be disposed between the filler material and the interior face of the tubular cover. In other words, the projecting edges 15a will extend away from the contact face of the bandage material so that seam 48 and the associated projecting edges 15a will not serve to irritate an injury upon which the bandage is placed. This operation completes the formation of the bandage strip or pad. As the encased filler material passes from the form 41, it is gripped by any suitable drafting means such as rollers 57 and 58 (Figure 1). These rollers are disposed upon shafts 59 and 60, said

shafts having intermeshing gears 61 and 62 respectively for driving the same. Shaft 59 extends to a gear reducing mechanism 63 which is driven by a motor 64, said mechanism 63 having a shaft 65 extending therefrom upon which a pulley 66 is mounted. Upon this pulley 66 a belt 68 is mounted, said belt being also mounted upon another pulley 69 of the sewing mechanism 50. This arrangement permits the sewing mechanism 50 to be operated in timed relation to the movement of the filler and cover materials.

It is therefore seen that means have been provided whereby the cover material may be fed sidewise into the former at an angle to the path of travel of the filler material, and that the edges of this cover material may be folded into substantially parallel superposed positions to each other so that the same may be formed into a tubular cover, and then employed to encase a filler material to form a completed bandage strip or pad.

Modified form of seam guide

Figures 14, 15, and 16 show a slightly modified form of the invention in which means are incorporated for rotating the tubular fabric around the hollow former 41 so that the seam 48 can be caused to occupy any desired position relative to the outer periphery of the filler material 53. In other words, it is often necessary to unite or seam the edges of the filler material when the same are disposed at one point on the periphery of the hollow former 41, and to subsequently rotate the seam and tubular member around the hollow former to another point on the periphery. This rotation may be as much as 90 degrees to locate the seam in the most remote position from the side edges of the bandage strip, while the tubular member is travelling in a general longitudinal direction.

The above-named rotation of the tubular cover is effected by means of a guide wire 75 and a guide plate 76. It is seen that the guide wire 75 has one end thereof secured to the outer side edge of the former 41 as at 77, said point 77 being disposed slightly below the horizontal center line of the former. The guide wire then gradually moves upwardly and outwardly for a substantial length of the tubular member, and then it moves inwardly above the former towards the longitudinal center line. The other end of the wire is secured as at 78 to the upper side of the former 41. When looking at the wire 75 in plan as shown in Figure 14, its shape resembles the letter S, and this wire causes the seam 48 to gradually travel inwardly towards the center former 41. A plate 76 is provided, said plate having a guiding edge 76a which cooperates with the guide wire 75 and serves to further direct the seam 48 inwardly towards the center line of the former. At the same time, the edge 76a rotates the tubular fabric further around the former 41. The two projecting edges of the tubular member are directed into parallel relationship to one of the faces of the tubular member, therefore, these edges will occupy a minimum amount of space and create a smaller rib in the completed bandage strip. In Figure 16 it is seen that the seam 48 and the projecting edges 15a are disposed in the above-named parallel positions before the tubular member is turned inside out and reversely directed to the interior of the former, as well as after turning and reversing. This type of bandage construction is employed when it is desired to remove the seam line 48 and pro-

jecting edges 15a still further from the side edges of the finished bandage.

Modified bandage forming structure

Figures 17 to 22 inclusive show still another modified form of the invention in which some of the same principles employed in the preceding form are present. In this form, however, means are provided for making a tubular cover out of two or more sheets of material and then reversing the tubular cover over a bat of filler material to form a bandage strip. This type of construction is preferable where it is necessary to employ one type of cover material upon the contact surface of the bandage and another type of cover material upon the surface which is removed from this contact surface.

Referring to Figure 17, a roll of material 85 is provided from which a sheet 86 passes. This sheet 86 travels downwardly beneath a roller 87, and then horizontally adjacent the upper side of a hollow former 88. (See Figure 18.) At the same time, another sheet of material 89 passes upwardly from a roll 90, over a roller 91, and then horizontally below former 88 in a substantially parallel position to the sheet 86. It should be noted that the sheet 86 passes above the former 88 while the sheet 89 passes beneath this same former, both of said sheets 89 being somewhat wider than the former to thereby provide projecting edges which can be united by any suitable means such as seams to form a tubular cover around the former 88.

The upper sheet 86 has its edges pressed downwardly upon the upper side of the former 88 and upon the edges of the lower sheet 89 in the manner shown in Figure 19 by means of a suitable brush 93. Immediately after the edges of the two sheets 86 and 89 have been pressed together in the manner shown in Figures 17 and 19, they are united by sewing mechanisms 94 and 95 which, in turn, form seams 96 and 97 respectively along opposed outer edges of the former 88.

As in the preceding case, the projecting edges 86a and 89a, which are disposed beyond the seams 96 and 97, must be folded into parallel positions to one of the faces of the cover material so that a minimum rib will be produced adjacent the seam line in the finished bandage. In order to effect this turning of the projecting edges substantially as described, suitable guide wires 99 and 100 are provided at opposed edges of the former 88 and adjacent the end of the forming tube where the material is reversed therethrough. It can be seen by observing Figures 18, 20 and 21 that the guide wires 99 and 100 extend outwardly and upwardly so that the seams 96 and 97 will be guided accordingly. In other words, the guide wires 99 and 100 have one end thereof attached near the lower edge of the tube 88 as at 99a and 100a respectively. It is at these points that the seam first engages the guide wire after the tubular member has been formed. The seam then follows the guide wires upwardly until the seam has been elevated to substantially the same position as shown in Figure 21 and when at this elevation the projecting edges 86a and 89a have been folded into parallel positions relative to the top layer 86. It will also be noted that the upper end of wires 99 and 100 are secured near the end of the tubular member 88 as at 99b and 100b respectively. When the tubular cover reaches the end of the hollow former 88, it is turned inside out and reversely directed through

the interior portion thereof and over a bat of filler material 102 to thereby form a finished bandage strip or pad in which the projecting edges beyond the seams are remotely disposed from the contact face of the bandage strip or pad. After leaving the former 88, the finished bandage strip passes between suitable drafting rollers 103 and 104, said drafting rollers serving to pull the cover sheets 86 and 89 from their respective rolls and also to pull the bat of material through the former along with the tubular cover.

The seam 48 is preferably formed from a thread of contrasting color to the tube of fabric. When the tube of fabric is turned along its longitudinal axis and is disposed away from the edges of the bandage and the like, the colored seam will indicate that this side is to be remotely disposed from the body surface to which the bandage is applied.

In the drawings and specification there has been set forth a preferred embodiment of the invention, and although specific terms are employed, they are used in a generic and descriptive sense only, and not for purposes of limitation, the scope of the invention being defined in the claims.

I claim:

1. Apparatus for continuously encasing a moving strip of filler material within a moving sheet of cover material, comprising means for folding said cover sheet into a U-shape in cross-section substantially along its longitudinal center line, a hollow form disposed at an angle to the line of travel of said U-shaped cover sheet, said form being adapted to receive said moving filler strip, means for reversely rotating the folds of said U-shaped cover sheet about said center line through an angle of substantially 180 degrees and over the exterior of said hollow form to thereby reverse the concavity of the U-shaped cover, means for forming a line of stitches near the edges of said U-shaped cover to form a tubular cover while the cover travels longitudinally over said form, means for reversely directly said tubular member at the end of said form, and then through the interior of said form over said moving filler strip whereby the filler material is encased in said tubular cover, the end of the form where the tubular member is reversed having a laterally extending member disposed at an angle to the longitudinal plane of the form to engage the flaps extending from the line of stitches to turn them both in the same direction against the side of the tubular member and away from the side edge of the form.

2. Apparatus for continuously encasing a moving strip of filler material within a moving sheet of cover material, comprising means for folding said cover sheet into a U-shape substantially along its longitudinal center line, a hollow form disposed at an angle to the line of travel to said U-shaped cover sheet, said form being adapted to receive said moving filler strip, means for reversely rotating the folds of said U-shaped cover sheet about said center line through an angle of substantially 180 degrees and over the exterior of said hollow form to thereby reverse the concavity of the U-shaped cover, means for uniting the edges of said U-shaped cover to form a tubular cover while the cover travels longitudinally over said form, means for axially rotating said tubular cover about the exterior of said form while the tubular cover travels longitudinally thereof, and means for reversely moving said tubular member over the end of said form and then through the

interior of said form, over said moving filler strip whereby the filler material is encased in said tubular cover.

3. Apparatus for continuously encasing a moving strip of filler material within a moving sheet of cover material, comprising means for folding said cover sheet into a U-shape substantially along its longitudinal center line, a hollow form disposed at an angle to the line of travel to said U-shaped cover sheet, said form being adapted to receive said moving filler strip, means for reversely rotating the folds of said U-shaped cover sheet about its line of travel, through an angle of substantially 180 degrees and over the exterior of said hollow form to thereby reverse the concavity of said U-shaped cover, means for uniting the edges of said second U-shaped cover to form a tubular cover while the cover travels longitudinally over said form, means on one edge of the form and engageable with said united edges for axially rotating said tubular cover about the exterior of said form while the tubular cover travels longitudinally thereof, and means for reversely moving said tubular member through the interior of said form and over said moving filler strip whereby the filler material is encased in said tubular cover.

4. Apparatus for encasing a strip of filler material within a tubular cover, comprising a hollow form around which said tubular cover is adapted to be positioned and through which said filler material is adapted to travel, means for axially rotating said tubular cover about the exterior of said form while the tubular cover travels longitudinally thereof, and means for reversely moving said tubular cover through the interior of said form and over said travelling filler strip whereby the filler material is encased in said tubular cover.

5. Apparatus for encasing a strip of filler material within a tubular fabric, said tubular fabric having a longitudinal seam therein, comprising a hollow form around which said tubular fabric is adapted to be positioned and through which said filler material is adapted to travel, means engageable with said seam for axially rotating said tubular fabric about the exterior of said form while the tubular fabric travels longitudinally thereof, and means for reversely moving said tubular cover through the interior of said form and over said travelling filler strip whereby the filler material is encased in said tubular cover.

6. Apparatus for continuously encasing a moving strip of filler material within a moving sheet of cover material, comprising a hollow form around which said moving sheet is adapted to be positioned and through which said filler material is adapted to travel, means for uniting the edges of said sheet to form a tubular cover while the sheet travels longitudinally over said form, means for axially rotating said tubular cover about the exterior of said form while the tubular cover travels longitudinally thereof, and means for reversely directly said tubular cover through the interior of said form and over said travelling filler strip whereby the filler material is encased in said tubular cover.

7. Apparatus for continuously encasing a moving strip of filler material within a moving sheet of cover material, comprising a hollow form around which said moving sheet is adapted to be positioned and through which said filler material is adapted to travel, means for uniting the edges of said sheet to form a tubular cover while the cover travels longitudinally over said form, means on the edge of the form for engaging one

edge of the tubular member and for axially rotating said tubular cover about the exterior of said form while the tubular cover travels longitudinally thereof, and means for reversely directing said tubular cover through the interior of said form and over said travelling filler strip whereby the filler material is encased in said tubular cover.

8. Apparatus for encasing a strip of filler material within a tubular cover, said cover having a longitudinal seam therein uniting adjoining cover sections along a line disposed in spaced relation to the edges of said sections whereby exteriorly projecting flaps will extend from said cover, comprising a hollow form around which said tubular cover is adapted to be positioned and through which said filler material is adapted to travel, means on one edge of the hollow form for engaging the seam for rotating said projecting flaps about said seam into substantially parallel positions with relation to each other and with relation to the adjacent cover while the cover travels longitudinally on the exterior of said form, and means for reversely directing said tubular cover and positioned flaps through the interior of said form and over said travelling strip of filler material to encase the filler material in the tubular cover.

9. Apparatus for continuously encasing a moving strip of filler material within a moving sheet of cover material, comprising a hollow form around which said moving sheet is adapted to be positioned and through which said filler material is adapted to travel, means for uniting adjoining cover sections along a longitudinal line disposed in spaced relation to the edges of said sections whereby exteriorly projecting flaps will extend from said cover, means on the exterior of the form for engaging the cover along the line where it is united for rotating said projecting flaps about said uniting line into substantially parallel positions to each other and also parallel to the adjacent cover while the cover travels longitudinally on the exterior of said form, and means for reversely directing said tubular cover and positioned flaps through the interior of said form and over said travelling filler strip to encase the filler material in the tubular cover.

10. Apparatus for encasing a strip of filler material within a tubular cover, said cover having a longitudinal seam therein uniting adjoining cover sections along a line disposed in spaced relation to the edges of said sections whereby exteriorly projecting flaps will extend from said cover, comprising an angularly disposed member for engaging the cover along said seam for rotating said projecting flaps about said seam into substantially parallel positions to each other and to the adjacent cover while the cover travels longitudinally and means for reversely directing said tubular cover and positioned flaps, and turning the cover inside out, and means for feeding the filler material into the cover as it is turned inside out to encase the filler material in the tubular cover.

11. Apparatus for forming a strip for surgical dressings, bandages, sanitary napkins, and the like, comprising an annular member, means for folding a continuously moving fabric and securing its edges together to form a tube, means for engaging the inside of the tube at the point where it is secured, and holding the tube in alinement with the securing means, and rotating the tube about its longitudinal axis, means on the outside of the tube for also engaging the tube at the

point where its edges are secured together for imparting further rotative movement to the tube, the annular member serving as means for reversing the direction of travel of the tube and turning it inside out, and means for feeding a web of filler material into the tube at the point where it is turned inside out.

12. Apparatus for forming a strip for making surgical dressings, bandages, sanitary napkins, and the like comprising means for folding a continuously moving fabric and sewing its edges together to form a tube, means for engaging the inside of the tube along the line of stitches formed by the sewing machine and holding the line of stitches in alinement with the sewing means and for also rotating the tube about its longitudinal axis, means on the outside of the tube for also engaging the tube along its seam line for imparting further rotative movement to the tube, means for reversing the direction of the travel of the tube and turning it inside out and means for feeding a web of filler material into the tube at the point where it is turned inside out.

13. Apparatus for encasing a strip of filler material within a tubular fabric, said tubular fabric having a longitudinal seam therein, comprising a hollow form around which said tubular fabric is adapted to be positioned and through which said filler material is adapted to travel, means on the inside of the tubular fabric engageable with said seam for axially rotating said tubular fabric about the exterior of said form while the tubular fabric travels longitudinally thereof, means on the exterior of the tubular fabric cooperating with the means on the interior of the tubular fabric for assisting the means on the interior of the fabric for axially rotating the tubular fabric about the exterior of said form, and means for reversely moving said tubular fabric through the interior of said form and over said travelling filler material whereby the filler material is encased in said tubular cover.

14. That method of encasing a lap of filler material within a tubular fabric which comprises yieldingly pressing together the opposed edges of a pair of longitudinally moving strips of material and at the same time maintaining the intermediate proximate faces of said strips in spaced relation to each other, uniting said strips by a pair of seams disposed in parallel spaced relation to the outer edges of the strips thereby providing a tube having exteriorly projecting strip margins beyond each seam line, folding the projecting margins about their respective seam lines into parallel positions with the exterior face of one of said strips and with relation to each other, turning said tube inside out and feeding a lap of filler material therein while maintaining said margins in said parallel positions relative to said strip face.

15. That method of encasing a strip of lap material which comprises uniting the edges of adjoining cover sections by a seam disposed in parallel spaced relation to the outer edges of said sections thereby providing a tube having exteriorly projecting margins beyond the seam line, folding the projecting margins about said seam line into parallel positions to each other and to the exterior face of one of said sections, turning said tube inside out and feeding a strip of lap material therein while maintaining said margins in said parallel positions relative to the face of said cover section.
